RULER

Charles H. Little, Cleveland Heights, Ohio, assignor of one-tenth to Charles Hubbard Little, Cleveland Heights, Ohio

Application February 3, 1936, Serial No. 62,144

1 Claim. (Cl. 33—107)

The present invention relates to drafting devices or instruments employed in drafting, and more particularly to a drafting ruler, either scale or straight edge.

5 Numerous attempts have been made in the past, as evidenced by my own prior art patents and otherwise, to produce a stiff, durable, light, easily readable ruler for drafting purposes which would not warp and which would be otherwise 10 satisfactory. At a very great expense I have made hundreds of experimental rulers from Celluloid, various kinds of wood treated in numerous ways, different metals and alloys, specially drawn tubing or bars, and various kinds of 15 stampings. In addition thereto, I have made numerous compound rulers comprising metallic and non-metallic cores encased or enclosed in Celluloid, etc. But prior to the present invention neither I nor others working along the same 20 line have been able to produce an entirely satisfactory drafting ruler embodying the aforesaid advantages.

An object of the present invention is the provision of a novel drafting device or ruler which 25 will be light, stiff, durable, and easily readable in the event graduations are marked thereon, which will not warp, and which will be otherwise satisfactory for the purpose intended.

Another object of the invention is the provision 30 of a novel drafting device or ruler comprising a metal body having edge strips formed of a plastic molded thereon and mechanically interlocked therewith.

Other objects and advantages of the present 35 invention will be apparent to those skilled in the art to which the invention relates from the following description of the preferred embodiments thereof, described with reference to the accompanying drawing forming a part of this specification, in which similar reference characters designate 40 corresponding parts throughout the several views, and in which

Fig. 1 is a plan view of a drafting device or ruler embodying the present invention.

45 Fig. 2 is a fragmentary perspective view showing the ruler in section on the line 2—2 of Fig. 1.

Figs. 3 to 8 inclusive are views similar to Fig. 2, each showing a different modified construction of the ruler shown in Figs. 1 and 2, with the 50 exception of Fig. 4a which is an enlarged partial section of the ruler shown in Fig. 4.

Figs. 9, 11, 13 and 15 are fragmentary perspective views of one end of a drafting device or ruler similar to that shown in Fig. 6, each figure 55 showing a different modified construction thereof.

Fig. 10 is a section on the line 10—10 of Fig. 9. Fig. 12 is a section on the line 12—12 of Fig. 11. Fig. 14 is a section on the line 14—14 of Fig. 13. Fig. 16 is a section on the line 16—16 of Fig. 15.

The drafting ruler A shown in Fig. 1 is of the type ordinarily referred to as a drafting scale and is especially adapted for use with drafting machines of the type shown in either of my United States Patents No. 1,909,289 or 1,909,291. The parallel or ruling edges of the scale are beveled as clearly shown in Fig. 2, and provided with suitable graduations, etc. Provision is made for chucking the device to the chuck or ruler supporting arm of a drafting machine, by providing opposite ends thereof with chucks 10 adjustably secured thereto as by screws 11. The two chucks shown permit the ruler to be reversed, that is, either end may be chucked to the chuck-arm of the drafting machine, as is the usual practice. The chucks are preferably made of duralumin 20 and given an oxide coating by a well known electrolytic process which gives the surface a coating that is free from glare and has a pleasing appearance, and which will not soil the drawing paper or surface.

In the embodiment of the invention shown in Figs. 1 and 2, the drafting device or ruler A is made entirely of a polymerization product of a vinyl compound, such as vinyl chloride, vinyl acetate, or vinyl benzene. These plastics have characteristics which adapt them peculiarly to the present use. Rulers made therefrom do not shrink or warp, are light in weight, durable, and easy to clean. The vinyl acetate is permanently nearly water white and when the ruler is made 35 therefrom the edges can be readily made transparent, in which event the graduations, if employed, may be placed on the under side. Commercially known plastics sold under the trade names "Vinolyte", "Vetro", "Galva", etc., which 40 are for the most part polymerization products of vinyl compounds, are suitable for the present purpose.

The polymerization products of the vinyl compounds can be molded at relatively low temperatures and pressures, and they have a very low and constant mold shrinkage, making it possible to mold graduations thereon very accurately and cheaply. The characteristics are also such that graduation and characters may be readily cut 50 therein. The material is tough and flexible without being brittle or unduly hard, which qualities give a superior wear resistance. It also feels well to the touch, keeps clean, and can be tinted various colors.

If greater stiffness is desired in the drafting ruler or device it can be obtained by providing the same with a metal core. Such a construction is shown in Fig. 3 which shows a drafting ruler designated generally by the reference character B, comprising a formed metal core 15 preferably steel encased within a plastic 16, preferably a polymerization product of vinyl acetate. The polymerization products of vinyl acetate cement especially well to metal and the coefficient of expansion thereof is approximately that of steel. The core may be of any shape and may be made in one piece, as shown, or comprises a plurality of pieces or members.

15 Instead of the entire ruler being made of the vinyl compound as illustrated in Fig. 1, or provided with a core as illustrated in Fig. 3, it may comprise a metal body, preferably duralumin, provided with edge strips preferably made of a 20 polymerization product of a vinyl compound molded thereto. In this event the ruler is preferably so constructed that there is a mechanical interlock between the edge strip or strips and the metal body. Fig. 4 shows a ruler designated 25 generally by the reference character C comprising edge strips 16 and 17 formed of a plastic and molded in position on the beveled edges of the body portion 18 and interlocked therewith by a plurality of rectangular tongues or projections 19 and 20 at right angles to each other formed 30 integral with the edge strip and engaging within suitable grooves in the upper side of the ruler body, and a tongue 21 also on the edge strip which projects inwardly and upwardly into an inclined groove in the underside of the body portion 18. The aforesaid construction provides a mechanical interlock between the ruler body and the edge strips so as to prevent movement in a number of directions.

35 Fig. 5 shows a ruler D wherein the edge strips 23 and 24 are connected to the ruler body 25 by a single dovetail tongue and groove supplemented by a rectangular tongue and groove adjacent the ruling edge of the plastic edge strip. 40 The body portion 25 has a channel formed in the underside thereof for the purpose of reducing the weight of the ruler. Fig. 6 shows a ruler E wherein the edge strips 26 and 27 are connected to the ruler body 28 by a plurality of dovetail grooves. As shown in Fig. 7 the entire beveled 45 portions of the ruler F are made of edge strips 30 and 31 likewise formed of a plastic and mechanically interlocked with the ruler body 32 by a single dovetail groove. Fig. 8 shows a ruler G, the construction of which is similar to that 50 shown in Fig. 7 except a "straight edge" type of ruler is illustrated instead of the "scale" type shown in the other figures.

In the foregoing figures the mechanical interlock between the edge strips and the body portion consist of tongues and grooves running longitudinally of the ruler, thereby holding the strips against movement particularly crosswise of the ruler body, but it will be apparent that other forms of mechanical interlock can be employed either alone or to supplement those shown. Figs. 9 and 10 show a ruler H similar in construction to the ruler E shown in Fig. 6, except that the body of the ruler is provided with two 55 transverse dovetail slots 36 adjacent the ends of the ruler in addition to the longitudinally extending slots, thereby positively holding the strips against lengthwise movement. If desired the longitudinal slots may be omitted entirely 60 and transverse slots employed alone. They may

be formed along the entire length of the ruler rather than at the ends only, as shown.

Another method of securing the edge strips to the beveled parts of the ruler body is by riveting the same thereto, either with or without the addition of other means for mechanically interlocking the parts. Figs. 11 and 12 show a ruler I, the edge strips 40 and 41 of which are riveted to the beveled edges of the ruler body by metal rivets 42 located adjacent the ends of the 10 ruler. As shown, the rivets 42 are supplemented by a mechanical interlock similar to that shown in Fig. 6. In some instances it may be desirable to have the heads of the rivets embedded in the edge strip as shown in Figs. 13 and 14, wherein 15 the ruler is designated generally by the reference character J, and the rivets, the upper ends of which are embedded in the edge strips 43 and 44, by the reference character 45.

A still further modified construction is shown 20 in Figs. 15 and 16. The ruler K shown in these figures is similar in construction to that shown in Fig. 6 except that the mechanical interlock shown in Fig. 6 is supplemented by projections 46 formed integral with the edge strips 47 and 25 48 adjacent the ends thereof, which projections extend into holes in the beveled edges of the ruler body. The holes are counterbored or beveled from the bottom and the result is a rivet formed integral with the edge strips. It will be 30 understood that, in the present instance as well as in the modifications illustrated in Figs. 11 and 13, rivets may be employed throughout the entire length of the ruler instead of merely at the ends as shown, either with or without other 35 means for mechanically interlocking the edge strips to the body portion. The particular constructions shown in Figs. 6, and 9 to 16 inclusive are claimed in a divisional application Serial No. 280,561, filed June 22, 1939.

40 In the construction shown in Figs. 4, 5, 6, and 9 to 16, the edges of the ruler bodies extend or project to some extent underneath the edge strips. This construction gives added support to the edge strip and protects the under metal surface of the body portion therebetween, but is not suitable when it is desired to employ transparent edge strips having graduations on the under surface. In the latter event the construction shown in Figs. 7 and 8 is preferred.

45 The edge strips which are made of a plastic are with all forms of my invention applied to the ruler bodies by molding under heat and pressure, and as previously stated, the graduations can be simultaneously molded therein during 50 their formation. During the molding operation the plastic flows into the interlock grooves, etc. in the ruler body and becomes cemented thereto forming a strong mechanical connection therebetween.

55 From the foregoing description of the preferred embodiments of the invention it will be apparent that the objects heretofore enumerated have been accomplished, and that a novel drafting ruler has been provided. While the 60 preferred embodiments of the invention have been illustrated and described, I do not wish to be limited to the construction shown which may be varied within the scope of this invention. It is my intention to cover all variations, adaptations and uses thereof that come within the 65 practice of those skilled in the art to which the invention relates, and I particularly point out and claim as my invention the following:

70 A composite drafting ruler comprising a ruler 75

body having a top beveled edge portion tapering outwardly and provided with grooves in the upper and the lower sides thereof, a V-shaped edge strip engaging around said beveled edge portion and formed from a plastic molded in position, a tongue on the underside of the upper prong

of said edge strip engaging within the groove on the upper side of said beveled edge portion, and a tongue on the upper side of the under prong of said edge strip engaging within the groove on the underside of said beveled edge portion. 5

CHARLES H. LITTLE.
